S. C. MEGILL, OF NEWARK, NEW JERSEY.

Letters Patent No. 72,519, dated December 24, 1867; antedated December 14, 1867.

IMPROVED RAILROAD-SWITCH.

The Schedule referred to in these Letters Patent and making part of the same.

TO ALL WHOM IT MAY CONCERN:

Be it known that I, S. C. MEGILL, of Newark, Essex county, New Jersey, have invented a new and improved Railroad-Switch; and I do hereby declare that the following is a full, clear, and exact description thereof, which will enable others skilled in the art to make and use the same, reference being had to the accompanying drawings, forming part of this specification.

This invention relates to a new and improved railroad-switch, of that class which are operated by the locomotive in case the switch, through the negligence of the switchman, should not be in line with the track on which the train is moving.

The invention is designed to obviate accidents, which frequently occur in consequence of the switchman failing to readjust a switch in line with the main track, after moving it to allow a train to pass from the branch track upon the main track, and *vice versa*. In the accompanying sheet of drawings—

Figure 1 is a side sectional view of my invention, taken in the line *x x*, fig. 2.

Figure 2, a plan or top view of the same.

Figure 3, a transverse vertical section of the same, taken in the line *y y*, fig. 2.

Similar letters of reference indicate corresponding parts.

A represents the rails of a main track; B, the rails of a branch track; and C, a switch constructed and applied in the usual way so as to form a connection with the branch track or a continuation with the main track, as may be desired, the ordinary hand-lever D being applied to the switch, and arranged in the usual or in any proper way. E represents what may be termed a three-armed lever, secured on the tie F, on which the free or disengaged end of the switch works. One arm, *a*, of this lever is connected by a rod, G, with the lower end of a bent lever, H, which is placed by the side of one of the rails A of the main track. The shape of this lever is shown clearly in fig. 1. The rod G is formed of two parts, connected by a joint, *b*, shown in figs. 1 and 2. Another arm, *c*, of this lever, which is in line with the arm *a*, is connected by a rod, I, with a bent lever, J, similar to H, and placed at the same side of the main track as H, but at the opposite end of the switch, the latter being between the two bent levers H J. The other arm, *d*, of the lever E is connected by a rod, *e*, with the switch, as shown in fig. 2. When the switch C is in line with the main track, the upper arms of the levers H J are sufficiently depressed to be below the reach of the flanges of the wheels of the locomotive, and hence cannot be acted upon by them. When the switch, however, is in line with the branch track, the upper arms of the levers H J will be sufficiently elevated to be acted upon by the flanges of the wheels, and depressed by them so as to throw the switch in line with the main track, the lever H or J being acted upon according to the direction in which the train may be moving. Thus by this simple means the switch C, in case of not being adjusted back, after being moved in line with the branch track for a train to pass thereon from the main track, and *vice versa*, will be moved or adjusted in line with the main track by the wheels of the locomotive.

When it is necessary to adjust the switch, so that a train can pass upon the branch track from the main track, the switch is moved by the switchman after the last car of the train has passed the lever H or J, it being designed in practice to have said levers sufficiently far from the switch to admit of this being done.

Having thus described my invention, what I claim as new, and desire to secure by Letters Patent, is—

The construction and arrangement of the bent lever E, pivoted to the tie F, its inner arm *a* connected to the bent lever H by the jointed rod G, its outer arm *c* connected to the angular lever J by the bent rod I, and its arm *d* pivoted to the transverse rod *e* bearing the switch-rails C, all operating as described, for the purpose specified.

S. C. MEGILL.
